UNITED STATES PATENT OFFICE.

FRANCIS W. GREMPLER, OF HOBOKEN, NEW JERSEY.

METAL-BEATING MACHINE.

SPECIFICATION forming part of Letters Patent No. 748,722, dated January 5, 1904.

Application filed April 11, 1903. Serial No. 152,109. (No model.)

To all whom it may concern:

Be it known that I, FRANCIS W. GREMPLER, a citizen of the United States, residing at Hoboken, in the county of Hudson and State of New Jersey, have invented certain new and useful Improvements in Metal-Beating Machines, of which the following is a full, clear, and exact description.

This invention relates to metal-beating machines, and has special reference to the means for shifting the package of metal undergoing treatment, so that the blow of the hammer will be delivered successively at varying distances from the center of the package and on successively-different radial lines.

The invention consists of specific means for moving the anvil or bed upon which the packet rests, as well as other features of construction.

In the accompanying drawings, Figure 1 is a front elevation of my improved machine. Fig. 2 is a side elevation thereof. Fig. 3 is a plan on line xx of Fig. 2. Fig. 4 is a section through the bed-plate, and Figs. 5 and 6 are details of the bed-plate mechanism.

A indicates the main frame of the machine, in the upper end of which the driving-shaft a is located. This carries a loose pulley a' , continuously rotating and having a clutch member a^2 in one face with which an opposing member a^3 is adapted to engage, the latter being keyed to the shaft and arranged to be thrown into and out of engagement by means of a bell-crank lever a^4 , pivoted on a shaft a^5 , on which there is a crank a^6 , moved by the hand-lever a^7 and link a^8 .

b is a rod mounted in a suitable part of the frame and carrying a brake-shoe b' , adapted to engage a pulley b^2 on the main shaft to bring the latter to a stop when the clutch is thrown out. In order that the brake may be simultaneously operated with the clutch, the lever a^3 engages with the brake-rod, as shown, while a spring b^3 determines the pressure of the brake against the pulley. At the forward end of the driving-shaft is a crank-disk a^8 , connected through pitman and slide a^9 with a vertically-reciprocating hammer a^{10} through the springs a^{11} , the latter furnishing the usual springy stroke required in metal-beating. Below the hammer is an anvil consisting of a frame C , provided on its upper surface with

a reciprocating carriage c , mounted in ways c' , along which it is adapted to slide in a direction transverse to the hammer. This carriage supports a ring c^2 , confined between segmental flanges c^3 , which are movable in a rotary direction in retaining-flanges c^4 .

The packet of metal and skins is to be placed upon the stationary anvil inside of the ring, with its corners fitting into notches in the ring, so that it will be moved bodily with the ring. Each of the segments c^3 has a slotted arm c^5 , into which projects a pin c^6 , carried by a sliding block c^7 . Thus when the block reciprocates the corresponding segment oscillates in a rotary direction. Each segment is provided with one or more inclined cavities c^8 , each containing a spring-pressed ball resting against the rim of the ring to act as a pawl. These pawls are so arranged that those of one segment only will grip the ring at the same time, and while the blocks c^7 are moved simultaneously in the same direction the ring will be acted upon by only one segment. This provides for a practically-continuous rotary motion of the ring in one direction. The sliding blocks c^7 have suitable dovetail connections with guides c^9 , and they are moved by crank-arms i on an oscillating shaft i' , mounted in the base of the anvil and having a crank i^2 at its middle point.

In a suitable bracket D offset from the base of the machine is mounted a shaft e , on which is loosely hung a double-armed lever f , having slots in each arm, in which are secured the ends of two rods h and j , respectively. The former connects with the crank i^2 and the latter connects, by means of a yoke j , with the carriage c . Radiating from the hub of the double arm is a projection k , carrying a roller which bears against the irregular rim of a cam-disk l , mounted upon a second shaft l' in the bracket D . The action of this cam upon the projection is to oscillate the double arm, and thus move the carriage c in one direction, while moving the blocks c^7 in the opposite direction. Both shafts e and l' extend through elongated bearings toward the rear of the machine, and the former is there provided with a ratchet-wheel e' , adapted to be engaged by a pawl e^2 , carried by a double arm e^3 , centered upon shaft e . On shaft l' is a gear-wheel l^2 , which carries a pin or roller l^3 ,

adjustable toward and away from the center and adapted to engage the arm e^8 at each rotation to force the ratchet-wheel e' forward step by step. The gear-wheel is driven by a 5 pinion e^4 , (shown in dotted lines in Fig. 2,) centered upon shaft e and attached to a pulley e^5 , which also turns upon the same shaft. This pulley is driven by belt e^6 from another pulley on the main shaft, as shown. One 10 face of the ratchet-wheel carries a flange e^7 , containing a notch adapted to be engaged by a roller e^8 on a crank-arm e^9 , to which the hand control-lever a^6 is fixed. At each rotation of the ratchet-wheel the roller drops into 15 the notch, permitting the clutch to open and the brake to be applied to stop the machine, the movement being effected by the spring b^3 or a spring suitably located at any other 20 point in the system of levers.

20 The operation is as follows: The package, made up of alternate pieces of metal and skins, is placed upon the anvil within the ring c^2 . The adjustment of the rods h and j in the slots of the double arm is made suitable for the first beatings to which the pack 25 is to be subjected. The machine is then started by lifting the handle of lever a^6 . This throws in the clutch, releases the brake, and releases the ratchet-wheel. The hammer 30 at once begins to beat the pack and the carriage slowly reciprocates, its motion being imparted through pulley e^5 , pinion e^4 , gear i^2 , cam l , projection k , and the double arm f , the 35 spring o acting upon the double arm in conjunction with the cam. The pack is thus pushed or dragged back and forth beneath the hammer and is struck each time a different distance from the center. Coincidently with the reciprocating motion of the carriage 40 the pack partakes of a rotary motion, due to the alternate engagement of the segments c^3 with the ring and the motion imparted to the segments through the arms i , shaft i' , crank i^2 , rod h , and the double arm. This 45 rotary movement being always in the same direction and being simultaneous with the rectilinear reciprocating motion of the carriage causes the blows of the hammer to be struck upon the pack at uniformly-changing 50 distances apart and along curved lines extending from the center toward the edge of the pack. It will be seen that the shape of each projection of the cam-disk l is that of a gradual incline on one side and an abrupt 55 incline on the other side. This provides for a quick return of the center of the pack beneath the hammer after the successive blows have been delivered from the center to the edge. The machine continues to run automatically until the notch in the flange of the 60 ratchet-wheel is again presented to the roller on the controlling-lever. When this takes place, the lever is allowed to move to stop

the machine. This permits an examination of the pack and of a different adjustment of the rods h and j in the slots of the double arm. It will be seen that by adjusting the position of rod h in the slot of arm f the rapidity of the rotary motion of the pack with respect to the number of its reciprocations in a given time can be controlled. This adjustment, together with that of the rod j , is desirable, since it enables the operator to direct the blows of the hammer at the proper points to produce the best results. Scales 70 can be engraved along the slots in the double arm to indicate the amount of each adjustment. When the machine stops, the hammer always comes to rest in an elevated position by reason of one side of the pulley 75 b^2 being weighted and seeking the lowest side of the wheel.

Having described my invention, I claim—

1. In a metal-beating machine, the combination of a carriage, means for reciprocating the same, a pack-holder carried thereby, means for rotating the same and means for varying the speed of rotation of the pack-holder independent of the movements of the carriage. 9c

2. In a metal-beating machine, the combination of a rotary pack-holder, reversed pawls acting upon the opposite sides of said holder, a reciprocating rod simultaneously actuating said pawls and an oscillating arm 95 with which said rod is adjustably connected, for the purpose set forth.

3. In a metal-beating machine, the combination of a rotary cam, a reciprocating carriage, a rotary pack-holder mounted on the carriage and mechanism whereby the cam actuates both the carriage and pack-holder. 100

4. In a metal-beating machine, the combination of a reciprocating carriage, a pack-holder carried thereby and having a rotary 105 movement independent of the movement of the carriage, an oscillating double arm and connections between the members of said arm and the carriage and pack-holder respectively whereby the carriage is reciprocated and the 110 pack-holder simultaneously rotated.

5. In a metal-beating machine, the combination of a reciprocating carriage, a pack-holder having a rotary movement thereon, a double-armed oscillating lever, connections 115 between the members of said arm and the carriage and pack-holder respectively for imparting said movements to said parts and a rotating cam adapted to oscillate said double-armed lever. 120

In witness whereof I subscribe my signature in presence of two witnesses.

FRANCIS W. GREMPLER.
